FIG. 1 is a perspective of an embodiment of our new disposable absorbent pants;

FIG. 2 is a front elevation thereof;

FIG. 3 is a rear elevation thereof;

FIG. 4 is a top plan view thereof;

FIG. 5 is a bottom plan view thereof;

FIG. 6 is a right side elevation thereof, the left side elevation being a mirror image of the right side elevation;

FIG. 7 is a plan view of the disposable absorbent pants of FIG. 1 with the pants unfolded and laid flat, the plan being of the surface of the pants that faces away from a wearer when the pants are worn; and,

FIG. 8 is a plan view similar to FIG. 7 but of the surface of the pants that faces the wearer when the pants are worn.
